UNITED STATES PATENT OFFICE.

STEPHEN KRONBURGER, OF JERSEY CITY, NEW JERSEY, ASSIGNOR TO COHAN-EPNER CO. INC., OF NEW YORK, N. Y.

DESIGN FOR A COMBINATION ASH TRAY AND MATCH RECEPTACLE.

61,416.

Specification for Design.

Patented Aug. 29, 1922.

Application filed November 14, 1921. Serial No. 515,133. Term of patent 7 years.

To all whom it may concern:

Be it known that I, STEPHEN KRONBURGER, a citizen of the United States, residing at Jersey City, in the county of Hudson and State of New Jersey, have invented a new, original, and ornamental Design for the Combination Ash Tray and Match Receptacle, of which the following is a specification, reference being had to the accompanying drawings, forming part thereof.

Fig. 1 is a plan or top view of the combination ash tray and match receptacle, and Fig. 2 is a side view of the same.

At one end of the ash tray is shown a pyramid having therein an opening for

matches; to the left of the pyramid is shown the figure of a camel in a kneeling position; to the right of the pyramid is shown a palm tree; at the foot of the pyramid are shown in bas-relief a scimitar, a star and a crescent, with the head of an Arab on the crescent.

At the other end of the ash tray there are two supports for cigars and above these a Turkish fez in bas-relief.

I claim:

The ornamental design for the combination ash tray and match receptacle as shown.

Signed this 29th day of October, 1921.

STEPHEN KRONBURGER.
